UNITED STATES PATENT OFFICE

2,170,680

SHOE FOR ROTARY IRONERS

George W. Dunham, Westport, Conn., assignor
to General Electric Company, a corporation of
New York

Application October 30, 1937, Serial No. 171,980

1 Claim. (Cl. 38—66)

The present invention relates to a shoe for rotary ironers.

Shoes for rotary ironers comprise a suitably heated metal plate having an arcuate surface which cooperates with a padded roll. Shoes have been customarily made by forming a sheet of hot rolled mild carbon steel to an arcuate shape and subsequently case hardening the shoe to provide a work contacting surface which would not become scratched by buttons and the like on the material being ironed. The case hardening operation invariably caused warping so that a subsequent straightening and grinding operation was necessary.

15 The object of my invention is to provide an improved construction and method of making a shoe for rotary ironers.

For a consideration of what I believe to be novel and my invention attention is directed to 20 the accompanying description and the claim appended thereto.

In the accompanying drawing, Figure 1 is a rear elevation of a rotary ironer equipped with a shoe embodying my invention; Figure 2 is a 25 sectional view taken on line 2—2 of Figure 1; and Figure 3 is a sectional view taken on line 3—3 of Figure 1.

Referring to the drawing, I have shown my invention applied to an ironer having a frame 1 supporting a suitably padded roll 2. Projecting from the frame is a tubular sleeve 3 in which is journaled a shaft 4 to which is fixed an arm 5 for supporting the shoe 6. The shoe comprises a metal plate 7 having an arcuate surface 8 35 cooperating with the roll and having longitudinal edges 9 each extending outwardly and forming an acute angle with the adjacent surface of the roll. The edges are connected by a reverse curved portion 10 having a curvature of the same order of magnitude as the central portion 40 of the shoe. The reverse curved portion 10 assists in feeding material between the roll and the shoe. It also stiffens the shoe. On the back of the plate 7 is fixed a bracket 11 which is pivotally connected by a pin 12 to the upper end of the arm 5. Upon oscillation of the shaft 4 the shoe will be moved toward and away from

the roll. The connection provided by the pin 12 permits pivotal movement of the shoe to equalize the pressure between the shoe and the roll. The rear surface of the shoe is enclosed by a cover plate 15 which is bolted to studs 16 welded to the rear side of the plate 7.

The shoe is heated by suitable electric heating elements 13 which are held against the rear side of the plate 7 by a clamping plate 14. The plate 14 is pressed against the heating elements by 10 clamping members 17 and nuts 18. The edges of the cover plate butt against the rear of the surface of the plate 7 and lie within the longitudinal edges thereof.

The plate 7 is formed from a sheet of twenty-point carbon steel which has been previously cold rolled to provide the desired surface hardness, for example, a hardness on the Rockwell B-scale of from 85 to 100. The sheet of cold rolled steel is formed to the shape illustrated. 15 The reverse curved portion 10 is necessary to provide a stiffening flange and a feeding edge for the shoe. It has a curvature of the same order as the body of the shoe, permitting the forming of the shoe from harder and more brittle 20 steel without fracture. After forming, the under side of the shoe may be polished and plated. Since the shoe is formed of pre-hardened material, there is no need for case hardening after 25 forming nor for the subsequent straightening 30 and grinding operations made necessary by warping during the case hardening.

What I claim as new and desire to secure by Letters Patent of the United States is:

A shoe for a rotary ironer comprising a metal 35 plate having an arcuate surface for cooperating with a roll and having the longitudinal edges extending outward at an acute angle to the adjacent surface on the roll, the edges being connected by a reverse curved portion having a curvature of substantially the same magnitude as the curvature of the central portion, and a cover plate fastened to and spaced from the rear side of the shoe, the edges of the cover plate butting and lying within the longitudinal edges of the 40 shoe.

GEORGE W. DUNHAM.
